FURNACE WALL STRUCTURE

George W. Davey, Worcester, Mass.

Application August 25, 1934, Serial No. 741,452
In Great Britain August 28, 1933

15 Claims. (Cl. 72—101)

The present invention relates to furnace wall structure and has particular reference to furnace wall structure of the kind comprising an outer supporting framework arranged to sectionally support an inner furnace wall comprising blocks of refractory material.

Heretofore refractory wall structures of the above character have been constructed so that the refractory blocks could be removed or inserted only from the inner or furnace side of the wall. In many instances this construction is a decided disadvantage particularly in cases where the wall is used in conjunction with so-called water walls comprising rows of water tubes adjacent to the furnace side of the refractory wall. Furthermore, in prior forms of sectionally supported furnace wall constructions, the refractory blocks sometimes break and frequently certain sections of the furnace wall deteriorate much more rapidly than others. When this occurs it is necessary to shut down the furnace and permit it to cool before repairs can be made. The disadvantage of having to shut down and cool an entire furnace in order to make a minor repair to a portion of the furnace wall is of course obvious. It is accordingly a general object of the present invention to provide a sectionally supported refractory furnace wall arranged so that the individual refractory blocks comprising the inner wall can be removed or inserted readily from the outside of the furnace. It is a further object of the invention to provide a wall of the character under consideration so arranged that the refractory blocks will be firmly held in place while at the same time being readily removed when desired. A still further object of the invention is to provide a sectionally supported refractory wall of simple and inexpensive construction that will provide the above enumerated advantages and in which leakage of air into the furnace between adjacent rows of refractory blocks is prevented by simple and inexpensive packing means. Still another object of the invention is to provide a novel form of refractory block for a wall of the character described which has relatively great structural strength and which is not likely to break in normal service.

The manner in which the above and other and more detailed objects of the invention are attained, together with the advantages to be derived from the use of the invention, will appear more fully in conjunction with the ensuing description of one practical embodiment of the invention which is illustrated in the accompanying drawing by way of example.

In the drawing:

Fig. 1 is a vertical section through a furnace wall structure embodying the invention, taken on the line 1—1 of Fig. 2;

Fig. 2 is a section taken on the line 2—2 of Fig. 1, certain of the blocks being broken away to more clearly illustrate a part of the supporting structure;

Fig. 3 is a perspective view of one of the refractory blocks shown in Figs. 1 and 2; and

Fig. 4 is an elevation of a portion of the block supporting structure.

In the embodiment illustrated, the outer supporting structure comprises a row of spaced vertical I-beam columns 10. A series of vertically spaced horizontal beams 11 are attached to the inner or furnace side of the columns 10 as by means of the bolts 12. As shown in Fig. 1, each of the beams 11 is of channel form in cross-section, the web of the channel being vertical and in contact with the flanges of the columns and the two spaced flanges of the beam sloping upwardly and inwardly away from the columns toward the furnace. Each horizontal beam serves to support a row of refractory blocks 14, each of which is diamond shaped in side elevation, the inner and outer faces of the block being vertical and the upper and lower faces sloping upwardly away from the outer face. The rear face of each block 14 is recessed to fit the beam 11 upon which the block is hung. To this end the outer face of each block is provided with two vertically spaced transverse grooves 15, each of the grooves sloping inwardly and upwardly from the outer faces in a direction parallel to the upper and lower faces 16 of the block. In addition, the portion of the outer face of the block between the grooves 15 is cut away slightly as at 16 in order to provide clearance for the web of the beam 11.

The horizontal beams 11 include removable sections 23 in the portions of the beam located between the columns 10. Each of the removable sections 23 is advantageously secured to the fixed portions of a beam 11 by means of splice plates 24 and studs 25, which are accessible from the outside of the wall.

Removable vertical plates 19 are advantageously secured to the outer flanges of the columns 10 by any suitable means such as studs 20, in order to provide vertical passages 21 between the adjacent columns through which air may be circulated for the purpose of cooling the blocks forming the inner wall.

In case it is desired to make use of a water wall the tubes forming such wall are placed adjacent

the inner or furnace face of the blocks 14, as shown at 18 in Figs. 1 and 2. With water tubes employed in the position shown in these figures, it is at once apparent that the blocks 14 cannot 5 be removed inwardly of the furnace and the construction in accordance with the present invention permits ready removal of the blocks outwardly of the wall in a direction away from the water tubes.

10 In order to prevent leakage of air into the furnace between adjacent horizontal rows of blocks while at the same time allowing clearance between the blocks of adjacent rows in order to compensate for expansion of the blocks and also 15 in order to facilitate removal and replacement of the blocks, transverse grooves 27 are provided in the upper and lower faces of the blocks and the space between these grooves is filled with a yielding insulating material such as asbestos rope or 20 the like.

From the foregoing description it will be apparent that the rows of refractory blocks are firmly held in position against the horizontal supporting beams by the action of gravity and that 25 since the blocks are supported by two flanges on each beam the maximum stress occurring on any one place within the block is materially reduced with consequently less chance of breakage. The clearance spaces provided between the adjacent 30 rows of refractory blocks effectively prevent the building up of a cumulative load on the blocks in the lower rows. The double support afforded for each block also minimizes the chance of tilting displacement of the blocks inwardly of the furnace. 35

The ease with which the blocks may be removed and inserted will be readily apparent from the drawing since to effect removal of the blocks it is only necessary to remove plates 19 and one 40 or more of the removable beam sections 23, which upon being disconnected from the fixed sections of the beams permit certain of the blocks to be removed outwardly of the wall in a direction parallel to the upper and lower faces of the blocks. 45 With the opening afforded by the removal of beam section 23 blocks supported by the adjacent fixed sections of the beam may be removed by sliding them laterally along the beam to the opening afforded by the removal of the section. 50 It will be understood that where packing such as that shown at 28 is employed it will be of sufficiently yielding character to permit the blocks to be moved into and out of position in the wall.

As will be apparent from the drawing the 55 structural steel necessary for the supporting framework is extremely simple and inexpensive both with respect to fabrication and with respect to erection and this simple framework provides the means for readily obtaining space for 60 circulation of cooling air over the exterior face of the wall, a highly desirable feature for walls subjected to very high furnace temperatures. Furthermore, the wall construction in accordance with the present invention is as well adapted for 65 use with water walls as it is for use in furnaces where the refractory wall is unobstructed on the furnace side.

While for the purpose of explaining the invention I have shown one suitable embodiment for carrying the invention into effect, it is to be understood that changes and modifications in the structure illustrated may be made without departing from the invention, the scope of which 70 is defined in the appended claims.

What I claim is:

1. A furnace wall structure comprising a row of spaced vertical columns, a series of vertically spaced horizontal beams carried by said columns, and a plurality of rows of refractory blocks removably carried by said beams, said beams including detachable sections located between said columns and removable from the wall structure outwardly thereof to provide spaces between the remaining sections of the beams for removal of blocks outwardly of the wall. 10

2. A furnace wall structure comprising a row of spaced vertical columns, a series of vertically spaced horizontal beams carried by said columns, a plurality of rows of refractory blocks removably carried by said beams, said beams including detachable sections located between said columns, and splice plates for connecting said sections to the fixed portions of the beams. 15

3. In a water cooled furnace structure having a row of water tubes, an outer framework including a row of vertical columns and a series of vertically spaced horizontal beams carried by said columns, and a plurality of rows of refractory blocks carried by said beams between the beams and said water tubes, said beams having removable sections located between said columns which when removed provide openings between remaining beam sections for removal of said blocks outwardly of the wall structure in a direction away from said water tubes. 20

4. In a water cooled furnace structure having a row of water tubes, an outer framework including a row of vertical columns and a series of vertically spaced horizontal beams carried by said columns, and a plurality of rows of refractory blocks hung on said beams, said blocks having recesses in their outer faces fitting said beams and the inner faces of the blocks being closely adjacent to said water tubes and said beams having removable sections located between said columns permitting removal of said blocks outwardly of the wall structure in a direction away from said water tubes. 35

5. A furnace wall structure comprising an outer framework including a series of vertically spaced horizontal beams each having two spaced upwardly and inwardly sloping flanges, and a plurality of diamond shaped blocks having recesses in their outer faces engaged by said flanges and sloping upper and lower faces parallel to said flanges, both of said sloping faces extending from the inner face of the block to the outer face thereof. 45

6. A furnace wall structure comprising a plurality of spaced vertical columns, a series of vertically spaced horizontal channel beams attached to said columns and having inwardly and upwardly sloping flanges, a plurality of diamond shaped refractory blocks having recesses engaged by said flanges and sloping upper and lower faces parallel to said flanges, said channel beams including detachable sections located between said columns to permit withdrawal of said blocks from said wall structure outwardly thereof and means for securing said detachable sections to the remaining sections of the beams. 60

7. A furnace wall structure comprising an outer framework including a series of vertically spaced horizontal beams, horizontal rows of refractory blocks hung on said beams, and packing means between adjacent rows of blocks, said blocks having upper and lower faces extending in upwardly sloping direction from the outer faces to the inner faces of the blocks and one 70

of said faces of each block being transversely grooved to receive said packing means.

8. A furnace wall structure comprising a row of vertical columns, a series of vertically spaced horizontal beams secured to said columns, said beams each having two spaced upwardly and inwardly sloping flanges and including detachable sections located between said columns, a plurality of rows of diamond shaped refractory blocks 10 hung on said beams having parallel upper and lower faces sloping parallel to said flanges from the outer faces to the inner faces of the blocks and outer faces recessed to fit said flanges, and packing means between adjacent rows of blocks, 15 said packing means being located in continuous grooves in said sloping faces and parallel to said beams.

9. For furnace walls, a refractory block having sloping top and bottom faces, both of said sloping faces extending from the inner face of the block to the outer face thereof, and an outer face having a plurality of spaced transverse grooves therein for engagement with a hanger beam.

10. For furnace walls, a diamond shaped refractory block having sloping top and bottom faces, both of said sloping faces extending from the inner face of the block to the outer face thereof, and an outer face having two spaced transverse grooves therein for engagement with a 30 hanger beam, said grooves extending into said block in a direction parallel with said sloping faces.

11. For furnace walls, a diamond shaped refractory block having top and bottom faces sloping from the inner face of the block to the outer face thereof and a recessed outer face providing two spaced and sloping transverse grooves parallel to said sloping faces for engagement with a hanger beam, the portion of the outer face between said grooves being cut back from the plane 40 of the remainder of said face.

12. For furnace walls, a diamond shaped re-

fractory block having top and bottom faces sloping from the inner face of the block to the outer face thereof, one of said faces having a transverse groove therein, and an outer face having two spaced sloping grooves therein parallel to the top and bottom faces of the block, the portion of the outer face of the block between said sloping grooves being cut back from the plane of the remainder of said face.

13. For furnace walls, a diamond shaped refractory block having upper and lower faces sloping from the inner face of the block to the outer face thereof, each of said faces having a transverse groove therein parallel to the outer face of the block and a recess in the outer face of the 15 block providing two spaced transverse grooves sloping in parallelism with said upper and lower faces.

14. A furnace wall structure comprising an outer framework including a series of vertically spaced horizontal beams and a plurality of refractory blocks carried by said beams, said blocks being generally diamond shaped in side elevation and having recesses in their outer faces adapted to fit said beams and said beams including detachable sections removable from the wall structure outwardly thereof to provide spaces between the remaining sections of the beams for removal of blocks outwardly of the wall.

15. A furnace wall structure comprising a row of spaced vertical columns, a series of vertically spaced horizontal beams carried by said columns, a plurality of rows of refractory blocks carried by said beams to provide a refractory inner furnace wall, said beams including detachable sections removable from the wall structure outwardly thereof to provide spaces between the remaining sections of the beams for removal of blocks outwardly of the wall and plates removably secured to the outside of said columns to provide air spaces between adjacent columns.

GEORGE W. DAVEY.
